BOILER STRUCTURE

Application filed August 30, 1928. Serial No. 302,940.

Our invention relates generally to liquid heating apparatus and has to do particularly with sectional boiler structure for use in connection with hot water heating systems, vapor systems, steam generating systems, etc., for heating buildings and other similar purposes.

One of the objects of our invention is to provide a simple, compact, highly efficient and inexpensive structure of the foregoing character which includes a plurality of separated water-containing and circulating units so arranged that products of combustion are caused to pass along in contact with the same in such a way as to provide for a most rapid and effective heating of the water in a minimum length of time with a minimum of loss of the heat units fired.

Another object is to provide a heating apparatus including a plurality of spaced fluid-containing sections which are formed of a metal having a high co-efficient of thermal-conductivity and which are so constructed and arranged relative to each other that generally vertical but tortuous gas-travel passages are formed therebetween whereby the gases of combustion passing through such passages are agitated and co-mingled to insure that all gases within the gas-travel and heat-transfer areas will be hot and fully effective.

Still another object is to provide gas-agitating means adapted to prevent the formation of cold, dead, inert and non-circulating gas films along the heat-transfer surfaces within the gas-travel areas thereby eliminating insulation of the heat transfer surfaces and, consequently, aiding in the transfer of a maximum amount of heat units through the heat-transfer surfaces.

A further and more specific object is to provide the exterior wall surfaces of some or all of the water-containing sections with gas-deflecting devices which, when the sections are assembled, extend horizontally into the gas travel areas and serve to agitate and deflect the upwardly flowing gases of combustion; and such devices are also formed of a metal of high thermal-conductivity and they increase the area of the heat-transfer surface along which the gases of combustion flow to

such an extent that a greater (and approximately the maximum) number of heat units in such products are absorbed by such devices and the section walls and transferred therethrough to the water within the sections so that the water is heated quickly and is caused to circulate rapidly.

An additional object of our invention is to accomplish the agitation of the products of combustion within the gas-travel areas by arranging the gas-deflecting devices on each wall of each section in spaced and staggered relation to each other and by arranging the deflecting-devices on the opposite walls of each section in staggered relation whereby, when two sections are assembled side by side in the intended spaced relation, the deflecting devices on each wall will not only assume a staggered relation with respect to each other but also to the devices on the opposite wall and no two of the directly opposed devices on the opposed walls will lie in the same horizontal plane. In further carrying out the objects of our invention, the deflecting and heat-transferring devices on each section wall are of such length and so spaced vertically and laterally that when the sections are assembled small vertical flue spaces are provided between the adjacent free ends of the devices on the opposed walls and similar spaces are provided between the devices on the same wall so that there is no objectionable restriction to the general upward flow of the gases of combustion. The gas-deflecting devices are also so arranged that the hot gases of combustion are deflected laterally against the walls of the fluid-containing sections thereby insuring greater heating efficiency from the heat units fired.

Another object is to provide for a sufficiently rapid circulation of the water through the sections to maintain the desired temperature-difference between the heat-exposed wall surfaces and the water-bearing surfaces thereby insuring the maximum heat-transfer to the water in a minimum length of time without danger of foaming, liming (and other well known insulating effects) which would tend to greatly lower heating-efficiency of the structure.

- Still another object is to provide highly efficient means for insulating the heating apparatus to conserve the heat and to maintain the water in its heated condition over long periods of time, and to, at the same time, insure against external influences affecting the heating-functions of the structure as a whole. To this end, the assembled water-containing sections are enclosed as a unit and dead-air spaces are provided around their exterior wall surfaces; and to simplify and cheapen the structure the exteriorly-exposed section surfaces are formed to provide, in conjunction with an outer covering, the foregoing dead-air spaces. This feature of our invention provides also for the mounting of the heating apparatus in small and confined spaces without danger of overheating adjacent wall surfaces and other objects.
- A further object is to provide a novel form of means for sealing the end spaces between the several sections, such means being self-supporting and easily detachable for readily inspecting and cleaning the gas-travel spaces between the sections.
- Additional objects are to provide a relatively large heat-transferring surface within a small gas-travel area; to provide for heating the water to the desired temperature in a single traverse through a relatively short water-traverse space; to provide a sectional boiler structure wherein the parts are so constructed and arranged that they may be easily and quickly assembled and disassembled; to provide a unitary structure, the capacity of which may be readily varied by the addition or removal of sections; to insure a long life for the boiler sections by eliminating insulating, and other, conditions which might tend to cause them to "burn-out"; and to provide for a minimum of fuel consumption with maximum benefit derived from the fuel fired whereby operating costs are reduced to a minimum.
- Other objects and advantages have to do with details of construction and arrangement of parts which will become obvious as this description progresses and by reference to the drawings, wherein,—
- Figure 1 is a front elevational view of a preferred form of water heating apparatus embodying our invention;
- Fig. 2 is an enlarged separated elevational view of one of the end water-containing sections and showing the inner face thereof;
- Fig. 3 is a separated elevational view of an intermediate water-containing section, the heat-transfer and deflecting projections on one wall being shown in full lines and part of the projections on the other wall being shown in dotted lines to more clearly illustrate the relative positions of these projections on the opposite walls of such section;
- Fig. 4 is an enlarged vertical section taken transversely through the lower part of the

structure of Fig. 1 at substantially the position indicated at line 4—4 of Fig. 10; the upper portion of the structure being cut away for convenience in illustration;

Fig. 11 is an enlarged sectional view through the burner structure and its support taken substantially on line 11—11 of Fig. 10.

The structure which we have chosen to illustrate our invention is gas-fired and is adapted for use in connection with a house-heating system. It includes a rectangularly shaped outer shell 15 (Figs. 1 and 8) which is formed, preferably, of four sections 15^a (front), 15^b (rear), 15^c (end) and 15^d (end)—fastened together as a rigid unit by corner angle-straps 16. A flue structure 17, including the flue discharge pipe 18, is supported by the upper edges of the shell sections.

The shell 15 encloses the water heating and circulating apparatus which includes a plurality of detachable water-containing sections (Figs. 4, 7 and 8). In the form shown, we employ six sections, two of which are end sections 19, 20 and the remainder intermediate sections 21, 22, 23 and 24. As will become obvious hereinafter the number of intermediate sections may be varied to vary the capacity of the apparatus.

These sections are mounted vertically side by side in spaced relation (Figs. 4, 5, and 8) providing so-called gas-travel passages or flues therebetween. The end sections 19, 20 extend from the floor, or other supporting surface, to the flue structure and serve to support the entire apparatus as will be described later. All of the sections are hollow to provide water spaces and the lower parts of the end sections are shaped to form hollow water legs 19^a, 20^a (Figs. 4 and 5). These water leg portions form the ends of a combustion chamber 25. These end sections are provided with internal webs 26 which add sufficient

strength to such sections as to render them capable of withstanding the pressure of the water, as well as the expansion and contraction conditions, without distortion and other detrimental effects. These webs are so located that they do not obstruct the desired free circulatory action of the water and ready draining of the sections.

The intermediate sections are shorter than the end sections and their bottoms terminate, preferably, in the plane of the upper portions of the end section water legs 19^a, 20^a so that such bottom portions define the top of the combustion chamber 25. These intermediate sections are each provided with strengthening webs 26^a similar to the webs 26 of the end sections.

Each of the sections 19 to 24, inclusive, is provided at the bottom portion with a similarly shaped and located hollow cylindrical and open-ended boss 27, the opposed faces of which are extended to form reduced annular shoulders 28, 28', which are adapted to receive one end of a connection-support nipple or bushing 29 (Figs. 5 and 6). The top front portions of the sections are provided with bosses and shoulders 39, 40 and 40' similar to the lower bosses and shoulders 27, 28, and 28' respectively, and they are adapted to also receive connection-support nipples similar to the nipples 29. When the sections are assembled (Figs. 4 and 5) the shoulders 28 and 28' of the lower bosses and the shoulders 40 and 40' of the upper bosses are, preferably, brought together in abutting relation. The nipples or bushings 29 are barrel-shaped so that when the sections are so brought together a fluid-tight flow connection is established at the top and bottom between adjacent sections. The right hand end section (looking at Fig. 1) is provided at the rear with an inlet 65 and the other end section is provided with a service outlet 66 so that the water, or other fluid takes a generally upward circulatory course from the inlet through the sections to the outlet. The bosses and shoulders at the top and bottom of the sections serve to space the sections to a predetermined extent to form the gas-travel passages therebetween and they, together with the nipples 29 serve to support the intermediate sections as will now be more fully described.

The end sections are each provided at their top and bottom edges with bifurcate lugs 30, 31 and 32 and a reinforced boss 33 having an opening therethrough (Figs. 2, 7, and 10). These lugs and bosses are adapted to receive the ends of tie rods 35, 36, 37 and 38 which are long enough to extend from one end section to the other. These rods may be of ordinary construction having a head at one end and threads at the other end to receive a nut 36' (Figs. 7 and 8). The sections are adjusted to and held in the relation shown in

the drawings by applying the tie rods as described and by tightening the nuts 36'. It will be understood that while we preferably arrange the adjacent sections so that the respective boss shoulders 28, 28', 40, and 40', 70 abut each other for increased rigidity and support, yet they may be spaced apart to form larger gas-travel passages without departing from our invention.

The opposite walls of each intermediate section are provided with a plurality of horizontal rows of spaced integral projections 41, 41^a which are rectangularly-shaped in outline and which taper in thickness from the section-wall surface to their free ends. When the sections are assembled as a unit, these projections project horizontally within the gas-travel passages formed between the sections and serve to increase the heat-absorbing and transferring surface as well as to 85 mingle the gases of combustion in the gas travel passage in such a manner as to increase the heating efficiency of such gases as will be described more fully hereinafter. The projections 41, 41^a on each wall of the intermediate section are staggered with respect to each other and the projections on one face of the intermediate section are staggered with respect to the projections on the opposite face of such section (Figs. 3 and 5). All of the 90 intermediate sections are of similar construction so that when placed side by side in the same relative positions, the projections on opposed faces of adjacent sections (Figs. 3 and 6) are staggered vertically and laterally with 100 respect to each other. These projections are of such length that when two intermediate sections are brought together (Figs. 3, 4, 5, and 8) the projections on the opposed faces do not extend far enough to project entirely 105 to or beyond the vertical plane in which the free edges of the projections on the opposed section walls lie. We have found in practice that excellent results may be obtained by spacing the opposed free ends of these projections approximately $1\frac{1}{8}$ inch apart. We have also found that excellent results may be obtained by similarly spacing the side edges of the staggered projections on the same section wall surface as indicated at B (Fig. 8). 110 Such spacing provides a plurality of vertical flue spaces B between the projections on the same section wall and a vertical flue space A (Fig. 8) between the ends of projections on opposed faces substantially $1\frac{1}{8}$ inch in width 115 in both instances. It is to be understood that the dimensions given are by way of illustration only and that we do not desire to be limited to the same, because, obviously, they may be varied without departing from our invention.

The end sections are provided with projections 42 and 42^a corresponding respectively to the projections 41 and 41^a on the intermediate sections. The projections on the right- 120 125 130

hand end section 20 (looking at Figs. 4 and 5) are arranged similarly (in staggered relation to each other) to the projections 41^a on the intermediate sections and the projections 42 on the left-hand end section are arranged similarly to the projections 41 on the intermediate section; and, when the end sections are brought together in the proper relationship to the intermediate sections (Figs. 4 and 5), the projections on the opposed section faces of each end section and the adjacent intermediate section assume a staggered position vertically and laterally as explained in connection with the opposed faces of two intermediate sections. With such an arrangement, all of the intermediate sections may be of similar construction and interchangeable thereby greatly facilitating addition and removal of sections to vary the capacity of the apparatus. The tie rod arrangement, as well as the mode of supporting the intermediate sections, also facilitates the handling of the sections for replacement, repair, etc., purposes.

The bottom portions of the intermediate sections are wedge shaped, being tapered inwardly as at 43, 44 so that, when the intermediate sections are placed side by side, flared throats or entrances 44^a leading to the gas-travel passages between the sections are provided. The inner wall surface of the end sections adjacent the top of the water-leg portions 19^a, 20^a, and in alignment with the tapered surfaces 43, 44 of the intermediate sections, are tapered in opposite directions so that they form with the adjacent intermediate sections flared throats or entrances 44^a similar to those between the intermediate sections. These throats serve to initially receive and direct the hot gases of combustion into the gas-travel passages between the sections as will be obvious from Fig. 4. Due to the arrangement of the projections 41, 41^a, 42 and 42^a on the section walls, the gases entering and flowing upwardly through the gas-travel spaces between the sections are caused to take a tortuous path, such gases being deflected laterally of the passage between the sections as well as in an endwise direction so that all gases passing through the space between the sections are co-mingled and kept in motion to prevent the formation of cool, inert, non-circulating and insulating gas films at any point along the surface of the sections.

If the projections were not arranged in the manner above described so as to bear a vertical and lateral staggered relation with respect to the projections on one face as well as the projections on the opposed face, there would be a tendency for the gases traveling upwardly under the influence of the draft in the flue structure to take the easiest vertical path and to by-pass the inner corner surfaces on the both sides of the projections. If the gases were permitted to by-pass these inner corner spaces, cool, dead, and inert gas films and pockets would be formed at that point which would tend to insulate the adjacent section surface against the oncoming hotter gases and the heat from such gases would be substantially all lost. Our invention provides against such a condition. Specifically, by reference to Figs. 4, 5, 6, and 8, it will be seen that, with our staggered arrangement of the projections, the gases in passing upwardly are deflected laterally in a plurality of directions and directly into the inner corner spaces indicated at C so that the gases at that point (and throughout the gas-travel passages) are always in motion and are active hot gases, and full benefit of the heat thereof may be received by a transfer of the same through the projections and the section wall to the water therein. The lateral spacing between the projections on the same section wall and between the ends of the sections on opposed walls provide for the desired freedom in the upward circulation action. Furthermore, these rectangularly shaped projections, in deflecting the gases laterally, cause such gases to strike directly against the vertical wall spaces of the sections between the projections whereby a greater number of the heat units fired are transferred directly through the section walls and the heating efficiency of the structure is greatly increased.

In addition to the foregoing functions of the projections 41, 41^a, 42 and 42^a, they also greatly increase the heat-exposed wall area of the sections whereby an exceedingly high percentage of the heat units in the products of combustion are absorbed and transferred to the fluid within the sections. Thus, the fluid within the sections is heated rapidly causing a rapid circulation of the fluid, and, as will be well understood, this rapid circulation tends to maintain the fluid-contacted surfaces of the sections at a relatively low temperature as compared to the temperature of the outer surfaces thereof. As a result of the maintenance of this proper temperature difference, the transfer of heat through the projections and the section wall surfaces is uniform and rapid thereby aiding in the absorption of a high percentage of the heat units contained in the products of combustion. The rapid circulatory action and the maintenance of this temperature difference prevents the formation of lime deposits, bubbles, etc., along the heat-transferring surfaces and eliminates other insulating conditions whereby the heat transferring action is such as to prevent overheating and "burning out" of the heat-exposed surfaces. As further results of this arrangement, the fluid is heated to substantially the desired temperature in its single traverse through the boiler structure; and such heating is accomplished with a minimum of fuel loss and, conse-

quently, at a lower operating cost than in devices heretofore used.

Any desired form of fuel may be employed for heating purposes. In the illustrated embodiment of our invention, we have shown an arrangement wherein gas is used as the fuel. Specifically, we provide the combustion chamber 25 located beneath the sections 19 to 24, inclusive. The ends of the combustion chamber, as above described, are formed by the water legs 19^a, 20^a of the end sections and the front and back of the same are formed by suitable plates 45 and 46 (Fig. 7). Within the combustion chamber, we provide a battery of burners 47 (Figs. 4, 7 and 11), one disposed centrally beneath each of the throats 44^a leading between the sections. Each of these burners comprises a head including three longitudinally extending and spaced gas distributing bars 47^a, 47^b, and 47^c each having a plurality of gas discharge orifices 48. The burner heads are supported upon mixture distributors 49 which extend outwardly through suitable openings in the front plate 45 of the combustion chamber for connection to a gas-distributor manifold 50. The inner end of each mixture distributor 49 is turned upwardly and is provided with a slightly tapered seat 55. Each burner head is provided with a central chamber 56 in communication with the gas distributing bars and which has an opening 57 on its underside adapted to receive the inner tapered end of the distributor 49. The wall of the opening 57 is shaped complementally to the inner end 55 of the distributor 49 so that the weight of the burner head wedges the same tightly upon the distributor to provide the desired gas-tight joint at that point (Fig. 11).

The burners are supported within the combustion chamber as follows: U-blocks 51 are formed on the lower surfaces of the end sections (Fig. 10) and they receive the ends of an inverted-channel strip 52. The horizontal web of the channel strip is provided with a plurality of longitudinal slots (one for each burner) for receiving the tongue 53 of a depending projection 54 on the burner-mixture distributor 49. The support is completed by the connection between the outer end of the mixture distributor 49 and the manifold 50, the manifold being supported by suitable brackets 60 attached to the front plate 45 of the combustion chamber (Figs. 7, 8 and 10).

To maintain the burners in horizontal alignment upon the mixture distributor seat 55, and to prevent relative rotation of the same, we provide the burner head with a depending lug 58 which extends between the bifurcated lug 59 on the mixture distributor 49 as clearly illustrated in Figs. 4 and 10. Equal distribution of the hot gases of combustion is aided by spacing the gas distributing bars 47^a, 47^b, and 47^c a predetermined distance and by spacing adjacent burners so that the adjacent bars

thereof assume the same spaced relation as the bars of the same burner as clearly shown in Fig. 7. In the foregoing manner, the burners and associated parts are firmly supported and maintained in a central position for discharging the hot gases of combustion directly into the throats 44^a between the sections and thence upwardly through the gas-travel passages to the flue structure 17.

The supply of gas to the manifold 50 may be controlled in any desired manner (manually, electrically, etc.) but we preferably control the same automatically by the temperature of the fluid in one of the sections. In the drawings, we have illustrated generally such a control, but since this control forms no part of our present invention, we will not show and describe the same in detail. Generally, we may provide in the supply pipe a pressure regulator 61 (Fig. 1) and an electrically-actuated device (solenoid or the like) 62 which operates under the influence of the temperature of the water to reduce or entirely cut off the flow of fuel to the burner as the conditions of operation may require. As shown clearly in Fig. 7, we also employ pilot burners 63 for the usual purpose, such pilots being under the control of electric pilot-control devices 64 which function, as it is well known, in conjunction with the electric device 62 to cut off the main supply of gas to the burners if the pilots 63 should, for any reason, fail. This arrangement renders the structure fool-proof and safe in operation. It further prevents unnecessary waste of fuel under general operating conditions.

The front plate 45 of the combustion chamber is detachably held in place by the thumb screws 72 for ready removal of the same for access to the burners within the combustion chamber. This plate is provided with two or more doors 73 pivotally mounted thereon as at 74 so that they may be swung sidewise to uncover suitable peep-openings and permit the operator to observe the interior of the combustion chamber. These doors may be provided with a plurality of transparent openings 75 which permit of casual observations of the conditions within the combustion chamber.

The ends (front and rear) of the spaces or gas-travel passages between the sections are closed to confine the gases of combustion to the heat-transfer area between the sections. Specifically, we employ at each end of each such space a seal plate 76 (Figs. 8 and 9). The sections are provided with upper projecting webs 77 and 78 and lower laterally projecting webs 79 (Figs. 2, 3, and 6) which extend inwardly toward each other when the sections are assembled. The ends of the seal plates 76 seat upon these webs to entirely close the end spaces of the sections. The seal plates (Fig. 9) are provided with inwardly extending and downwardly-inclined lugs 76^a

which are long enough and are so positioned along the plates as to hook over the adjacent projections 41, 41^a, 42, and 42^a of the end and intermediate sections to support the plates. The weight of each of the plates 76 is sufficient to wedge the same inwardly and tightly against the adjacent end surfaces of the sections to seal the plate against such surfaces. This wedging action also prevents accidental displacement of the plates but, at the same time, renders them quite easily removable without the attachment of any parts such as bolts, nuts, etc.

Another important feature of our invention is the manner of insulating the water-containing sections so as to conserve heat, to maintain the water in its heated condition for maximum period of time and, generally, to prevent outside influences from affecting the functioning of the heating apparatus and to increase the efficiency of the apparatus as a whole. In carrying out this feature of our invention, we provide an insulating jacket (Figs. 4, 7, and 8) which includes the outer shell 15 and insulation sections 15^a (front), 15^b (rear), 15^c (end), and 15^d (end). These insulation sections are each formed, preferably, (but not necessarily) of slabs of insulating material such as rock wool, asbestos, etc., and they each take the generally-rectangular shape of the adjacent shell wall. The front insulation section 15^a extends from the top of the shell to upper edge of the front combustion chamber plate 45; and the rear and end insulation sections extend from the top to the bottom of the shell. These insulation sections are associated with the adjacent surfaces of the fluid-containing sections in such a way that separated dead air spaces are formed entirely around the exterior, exposed walls of the assembled section-unit. Specifically, the opposite ends of the fluid-containing sections are provided with a plurality of spaced, parallel and horizontally extending ribs 80, 80', which extend, preferably, almost across such end surfaces. The end surfaces of the end sections 19, 20 are extended, as at 19^b, 20^b to form vertical flanges projecting beyond the outer wall of the end sections. The end section outer walls are provided with spaced, parallel and horizontal ribs 81, 81', extending entirely thereacross from the flange at one end edge to the flange at the other end edge. The seal plates 76 are also provided with ribs 76^b which align, respectively, with the ribs on the ends of the sections; and the rear combustion chamber plate 46 is likewise provided with ribs 46^a similar to the ribs 81 on the adjacent end sections. When the insulating jacket is assembled upon the section-unit (Figs. 1, 4, 7, and 8) the inner face of the front insulating section 15^a abuts the outer ends of the ribs 80 (front) so as to divide the front surface into a plurality of dead air pockets 82 (Fig. 10); the rear insulating section 15^b abuts the rear wall ribs 80' forming dead air pockets 83; and the end insulating sections 15^c and 15^d abut the end ribs 81, 81' forming, respectively, dead air pockets 84 and 85 (Fig. 4). Thus, the dead air spaces are formed entirely around the exposed surfaces of the section-unit and, as will be appreciated, the insulating efficiency is greatly increased. This very desirable feature is provided for in an exceedingly simple and inexpensive manner.

The operation of the structure as a whole will be obvious from the foregoing. The fluid to be heated enters the end section at the right (looking at Fig. 1) through the inlet pipe 65 and this fluid circulates generally upward through the sections, being, at the same time, heated to substantially the desired temperature, and it eventually passes outwardly through the service or discharge pipe 66 which may lead to heat-radiating devices in the building to be heated or to any other desired discharge point. The spent gases of combustion which pass between the fluid-containing sections are discharged through the top-open spaces between the sections into the flue structure 17 and are carried away through the flue pipe 18. Drain connections 86, 86^b (Fig. 4) are provided at the bottom of each water leg 19^a, 20^a for conveniently draining the sections. These drains may be controlled in any desired manner, and one or both may be used. In some instances, the drain connections 86, or a similarly located connection, may be utilized as the fluid inlet.

Near the upper end of the right hand end section 20, and connected therewith, we provide a pop-valve structure 67 of ordinary form as an additional safety measure, in case other of the safety devices should fail. We also provide a further safety structure 68 of well-known form which is connected to the right end section and which functions, preferably, under electrical control in conjunction with the electrical device 62 to cut off the gas supply in case the fluid in the section is reduced below the desired level or in case the fluid in the sections becomes too hot or the steam pressure gets too high. The structure 68 includes the usual pressure gauge 69, glass water-gauge 70 and level-test-cocks 71.

While we have shown and described only one form of structure embodying our invention, it will be understood that various changes in details and arrangement of parts may be made without departing from the spirit and scope of our invention as defined by the claims which follow.

We claim:

1. In a liquid heater, a combustion chamber, a plurality of hollow liquid-containing sections arranged side by side in spaced relation, the spaces between said sections form-

ing gas-travel passages in communication with said combustion chamber, and heat-absorbing transferring means including a plurality of rows of flat projections on the opposed faces of said sections and extending within the gas-travel area between said sections, said projections on one section wall being staggered vertically and horizontally with respect to those on the opposed section wall to positively deflect the gases flowing through said passages lengthwise and side-wise thereof beneath the projections on both opposed faces.

2. In a liquid heater, a combustion chamber having means therein for discharging hot gases of combustion; a plurality of spaced hollow fluid-containing sections, the spaces between said sections constituting gas-travel passages through which the gases of combustion flow, and the walls of which constitute heat-absorption-transfer surfaces; a plurality of rows of spaced heat-absorbing transfer projections on the opposed walls of said sections, said projections in one row of each wall being staggered with respect to the adjacent projections on that same wall area, the said projections on opposed walls being also staggered with respect to each other, all said projections extending horizontally into the respective gas travel passage.

3. In a liquid heater, a combustion chamber having means therein for discharging hot gases of combustion; a plurality of spaced hollow fluid-containing sections, the spaces between said sections constituting gas-travel passages through which gases of combustion flow from said combustion chamber, and the walls of which constitute heat-absorption-transfer surfaces; a plurality of rows of solid-section, rectangularly-shaped and spaced heat-absorbing transfer projections extending integrally in a horizontal direction from the opposed walls of said sections, said projections in one row of each wall being staggered with respect to the adjacent projections on that same wall area, the said projections on opposed walls being also staggered with respect to each other, all said projections extending horizontally into said gas-travel passage, and the plane of the ends of the projections on one wall is spaced from the plane of the ends of the projections on the other wall.

4. In a liquid heater, a combustion chamber having means for discharging hot gases of combustion; a plurality of spaced fluid-containing circulating sections, the spaces between said sections constituting gas-travel passages; a plurality of horizontal rows of spaced integral projections extending from the opposed walls of said sections, the projections in adjacent rows on the same wall being staggered with respect to each other and the spacing between the said projections on the same wall being so arranged that rela-

tively small vertical passages are provided along that same wall between said projections, and the adjacent of said projections on the opposed walls being disposed in staggered relation to each other so that the free ends 70 of said opposite projections are not directly opposite each other.

5. In a liquid heater, a combustion chamber having means for discharging hot gases of combustion; a plurality of spaced fluid-containing circulating sections, the spaces between said sections constituting gas-travel passages; a plurality of horizontal rows of spaced integral projections extending from the opposed walls of said sections, the projections in adjacent rows on the same wall being staggered with respect to each other and the spacing between the said projections on the same wall being so arranged that relatively small, unobstructed, vertical passages 80 are provided along that same wall, and said projections on the opposed walls being also arranged in staggered relation to each other so that the free ends of said opposite projections are not directly opposite each other, 90 and the plane of the ends of the projections on one wall is spaced from the plane of the ends of the projections on the other wall whereby a relatively small, unobstructed, vertical flue space is provided at the center 95 of said gas-travel passage substantially of the outline-size of said sections.

6. In a fluid heater, the combination of a fire chamber, a plurality of fluid containing sections disposed in spaced relation, a discharge flue above said sections, the spaces between said sections being in communication with said fire chamber and flue, and heat absorbing devices extending horizontally and projecting laterally from the exterior walls 100 of said sections into the spaces therebetween, said devices being arranged in rows and the devices in each row on each wall being spaced and the devices in adjacent rows on the same wall being staggered, and the devices on opposite walls of said sections being so located with respect to each other that they assume a staggered relation whereby the free ends of 105 said devices extending into said space are not directly opposite each other.

7. In a fluid heater, the combination of a fire chamber, a plurality of fluid containing sections disposed in spaced relation, a discharge flue above said sections, the spaces between said sections being in communication with said fire chamber and flue, and heat absorbing devices extending horizontally and projecting laterally from the exterior walls 110 of said sections into the spaces therebetween, said devices being arranged in rows and the devices in each row on each wall being spaced and the devices in adjacent rows on the same wall being staggered, and the devices on opposite walls of said sections being so located with respect to each other that the devices 115

on one wall are offset vertically and laterally with respect to the devices on the opposed wall whereby products of combustion entering said space from said fire chamber are deflected laterally in all directions within said space and particularly into the corner spaces formed between said devices and their supporting walls.

8. A liquid heater comprising a combustion chamber from which are discharged hot gases of combustion; a flue structure; a plurality of liquid-containing sections mounted side by side in spaced relation forming gas-travel passages therebetween which are in communication at one end with said combustion chamber and at the other end with said flue structure; and heat-absorption-deflection means carried by the exterior walls of said sections and associated with said gas-travel passages for increasing the heat-transfer area within said gas-travel passages, said means comprising flat-face projections extending away from the walls of said sections, said projections on one face of a section being so positioned that they are offset vertically and horizontally relative to the projections on the face of the opposed section, and the vertical and horizontal offsetting of said projections on opposed faces being of such dimension that gases deflected from one projection toward the opposed section travel upwardly and substantially directly beneath the next-above vertically offset projection whereby the gas-travel passage areas beneath said projections are constantly swept positively by hot gases.

9. A liquid heater comprising a combustion chamber from which are discharged hot gases of combustion; a flue structure; a plurality of liquid-containing sections mounted side by side in spaced relation forming gas-travel passages therebetween which are in communication at one end with said combustion chamber and at the other end with said flue structure; a plurality of horizontal projections extending from said sections into said gas-travel passages and arranged in horizontal rows, the projections in adjacent rows being staggered with respect to each other; and the projections on the opposed section walls being so displaced with respect to each other that the projections on one wall are offset vertically and laterally with respect to the projections on the other wall so that they do not extend end to end.

55 10. A liquid heater comprising a combustion chamber from which are discharged hot gases of combustion; a flue structure; a plurality of liquid-containing sections mounted side by side in spaced relation forming gas-travel passages therebetween which are in communication at one end with said combustion chamber and at the other end with said flue structure; a plurality of solid-section, flat, horizontal projections extending from said sections into said gas-travel passages and

arranged in horizontal rows, the projections in adjacent rows being staggered with respect to each other; and the projections on each wall in each row having their adjacent edges so spaced as to provide relatively narrow vertical spaces between the projections along the section wall, and the projections being of such length that the ends of those on opposed section walls do not extend into the same vertical plane thereby leaving a relatively narrow vertical space between the ends of opposed projections within the gas-travel passages.

11. A liquid heater which includes a unit having a plurality of liquid-containing chambers, means for passing hot gases of combustion along the walls of said chambers within said unit; and means for insulating said unit including an insulating jacket surrounding said unit, the outer wall surfaces of said unit having connected vertical and horizontal ribs defining sections which engaged by said jacket form relatively small, confined dead-air pockets between said jacket and unit.

12. In a liquid heater, a plurality of liquid-containing sections secured together side by side in spaced relation to form gas-travel passages therebetween, means for discharging hot gases of combustion into said passages; and means for insulating said sections including a heat-insulating jacket disposed around the exposed walls of said assembled sections, said sections having their outer exposed walls ribbed vertically and horizontally whereby when said jacket is placed therearound in contact with said ribs relatively small, confined dead-air insulating spaces are formed between said jacket and the adjacent walls of said sections.

13. In a liquid-heater, end liquid-containing sections; intermediate liquid-containing sections between said end sections; means for rigidly securing all said sections together side by side in vertical spaced relation as a unitary structure; means for passing hot gases of combustion between said assembled sections; a plurality of spaced members projecting horizontally from the end wall surfaces of all said sections; a plurality of similar members projecting vertically and horizontally from the outer and exposed side walls of said end sections; and a jacket formed of insulating material surrounding all said sections and abutting said members to provide separated, confined dead air spaces between said jacket and the section surfaces carrying said members.

14. In a liquid heater, end liquid-containing sections; intermediate liquid-containing sections between said end sections; means for rigidly securing all said sections together side by side in vertical spaced relation; means for passing hot gases of combustion between said assembled sections; and insulating means including spaced, parallel, horizontally and

- vertically projecting ribs extending across the exposed wall surfaces of said sections, and an insulating jacket surrounding said sections and abutting the free ends of said ribs for forming a plurality of disconnected, confined dead-air insulation spaces around said assembled sections.
15. In a liquid heater, end liquid-containing sections; intermediate liquid-containing sections between said end sections; means for rigidly securing all said sections together side by side in vertical spaced relation; means for passing hot gases of combustion between said assembled sections; seal plates covering the ends of the spaces between said sections to confer the gases of combustion therebetween; spaced, horizontal ribs projecting from the vertical end wall surfaces of all said sections; similar aligned ribs on said seal plate; similar ribs projecting from the vertical outer side wall surface of the end sections; and a jacket formed of insulating material disposed around said sections and spaced therefrom by said ribs to form separated, confined dead-air spaces around the entire outer surface of said assembled sections.
16. In a liquid heater, end fluid-containing sections having fluid-containing leg portions for supporting the same, said leg portions forming opposed walls of a combustion chamber; intermediate liquid-containing sections between said end sections and supported thereby with their bottoms above said combustion chamber, said sections being spaced apart to form gas travel passages therebetween, separate plate members bridging said water-legs and forming the other walls of said combustion chamber; parallel fins extending substantially across and projecting horizontally from the end wall surfaces of all said sections; similar fins on the outer side wall surfaces of said end sections and on the leg portions thereof; similar fins on at least one of said combustion chamber wall plates; vertical fins on certain of said wall surfaces contacting some of said horizontal fins and a jacket of insulating material disposed around said sections, upon said leg portions and upon at least one of said plates and contacting the projecting ends of said fins to form a plurality of relatively small-separated, confined dead-air spaces around the walls of said sections exposed to said jacket.
17. In a liquid heater, end liquid-containing sections; intermediate liquid-containing sections between said end sections; means for rigidly securing all said sections together side by side in vertical spaced relation; means for passing hot gases of combustion between said assembled sections; a plurality of spaced members projecting horizontally outward from the end wall surfaces of all said sections; outwardly projecting vertical flanges on the edges of said end sections; a plurality of spaced horizontally-disposed members on the outer side wall surfaces of said end sections bridging said flanges and forming on those side wall surfaces a plurality of pockets; and a jacket formed of insulating material disposed around said sections abutting the free ends of all said members closing said pockets and forming dead air spaces around said sections.
18. A liquid heater of the sectional type including a plurality of liquid-containing sections vertically disposed side by side and spaced apart to form therebetween at least one gas-travel space, a seal plate adapted to be mounted over each of the open side edges of said side space to close the sides of said space, heat absorption members projecting horizontally from the opposite walls of said sections and inwardly of said gas-travel passage, and integral, downwardly inclined hook-lugs on each said plate adapted, when said plate is in sealing position, to project into said gas-travel passage and hook downwardly over the adjacent of said members to provide the sole attachment for said plate in sealing position, and in readiness for removal of said plate without removal of any detachment parts and by mere upward and outward movement of said plate.
19. A liquid heater of the sectional type including a plurality of liquid-containing sections vertically disposed side by side and spaced apart to form gas-travel spaces therebetween, seal webs on said sections at the top and bottom of said gas-travel spaces and projecting across the open side edges thereof, seal plates adapted to be mounted over the open side edges of said spaces with their ends in sealing abutment engagement with said webs to close the sides of said spaces, heat absorption members projecting horizontally from the opposite walls of said sections and inwardly of said gas-travel passages, and downwardly inclined hook-lugs on said plates adapted to project into said gas-travel passages and engage the adjacent of said members to support said plates in sealing position against said webs and section surfaces, but to permit ready removal of the same without removing any attachment parts by upward and outward movement of the same.
20. In a liquid heater of the sectional type, a combustion chamber, a plurality of hollow liquid-containing sections arranged side by side in spaced relation, the space between adjacent sections forming a gas-travel passage in communication with said combustion chamber, a plurality of rows of spaced, flat projections extending flat-wise within the gas-travel area between said sections, said projections being of such length and so positioned with respect to each other on the same and on the opposed sections that the gases of combustion are positively deflected simultaneously in a plurality of horizontal directions at substantially right angles to each other at

numerous points in said gas-travel area whereby the gases are caused to swirl throughout said area against the vertical side-wall surfaces of said sections in the generally-upward travel of the gases.

5 In witness whereof, we have subscribed our names.

JAMES PATRICK MORLEY.
SIMON JOSEPH LONERGAN.

10

CERTIFICATE OF CORRECTION.

Patent No. 1,857,471.

Granted May 10, 1932, to

JAMES PATRICK MORLEY ET AL.

It is hereby certified that error appears in the printed specification of the above numbered patent requiring correction as follows: Page 9, line 16, claim 15, for the word "confer" read confine; and that the said Letters Patent should be read with this correction therein that the same may conform to the record of the case in the Patent Office.

Signed and sealed this 21st day of June, A. D. 1932.
